UNITED STATES PATENT OFFICE

2,608,025

TOY SKY-WRITING AIRPLANE

Walter E. Miller, West Hartford, Conn.

Application June 16, 1950, Serial No. 168,489

2 Claims. (Cl. 46—9)

1

This invention relates to toy airplanes and more particularly to such toy airplanes as are whirled around in the air at the end of a cord to imitate stunt flying.

It is an object of this invention to provide a toy airplane of novel construction, having means therein for producing a buzzing noise, while the airplane is being whirled around, to imitate the noise of a real airplane engine and thereby render the toy more attractive.

It is a further object of the invention to provide such a toy airplane having novel means for imitating sky-writing.

Further objects and advantages of this invention will be more clearly understood from the following description and the accompanying drawings in which:

Fig. 1 is a plan view of a toy airplane embodying my invention.

Fig. 2 is a front view thereof.

Fig. 3 is a sectional front view on line 3—3 of Fig. 1.

Fig. 4 is a sectional side view of my improved toy airplane.

Fig. 5 is a front view, on a reduced scale, showing the manner in which my toy airplane is used.

Fig. 6 is an enlarged side view of the powder container used in connection with my present invention.

In the preferred embodiment of my invention which is illustrated, my improved toy airplane is in the form of a monoplane having a hollow fuselage 5 and a pair of wings 6—6 extending from the sides thereof. The fuselage also has stabilizers 7—7 and a rudder 8 at the end thereof.

In accordance with the present invention, the inner end of each wing is constructed to provide a horizontally divided portion 9, having an air opening 10 extending therethrough in the direction of the longitudinal axis of the fuselage. These passages in the opposite wings communicate across the interior of the fuselage through openings 11—11 in the side walls thereof, and the said fuselage is also provided with a front opening 12 and a rear opening 13 to permit the passage of air longitudinally through the fuselage.

In order to cause a buzzing, or humming, noise while the plane is being moved through the air, I provide a series of thin rubber strips 14 which are stretched across the air passages 10—10 in the wings and extend through the interior of the fuselage. These strips are preferably in the form of rubber bands and are extended over the tops of the upper portions 15—15 of the wings and through the walls of the fuselage and across

the interior thereof so as to provide additional stretches 16 of said rubber strips between raised projections 17 and 18, on each of the wings, which space the stretches 16 from the portions 15.

5 My present invention also includes novel means for imitating "sky-writing," such as is commonly done with the use of smoke or the like that is ejected from an airplane while in motion.

Such means preferably comprise a suitable container 19 which is supported upon the longer

10 stretches 14 of the rubber bands that extend across the air passages 10—10. This container is provided with a filler tube that has a closure 21, and extends upwardly from the container through an opening in the top of the fuselage that is large enough to permit free movement of the tube and the container. The bottom of said container has an orifice therein which opens through a connecting tube 22 into an air tube 23 that is supported substantially in line with the air opening 12 and has a funnel shaped forward portion 24. Various materials may be placed within the container 19 to imitate smoke, but I have found that a common form of talcum powder or 15 the like, which is easily obtainable, may be used to produce the desired effect. This powder, which is indicated at 25, may be placed in the container through the filler tube 20.

20 It will be noted that the container 19, with the tubes 20 and 23 thereon, is supported entirely upon the rubber bands so that it may move therewith as the said bands are vibrated.

25 In the use of my improved toy airplane, a string or cord is secured to a suitable loop 26 on the fuselage and the plane is whirled through the air in circles, figure eights, dives and various other maneuvers to imitate stunt or exhibition flying. During the whirling of the plane, air will rush through the passages 10—10 and cause the 30 rubber strips 14 therein to vibrate and produce sounds imitating the noise of an airplane in flight. If desired, the said strips may be stretched unevenly so as to produce sounds of different pitches which may even be harmonized. The 35 passage of air over the portions 16 of the rubber strips will cause them to vibrate and add to the humming or buzzing noise produced by the 40 strips 14.

45 When it is desired to produce an imitation of "sky-writing," a powder is placed within the container 19 before the plane is whirled through the air. Vibration of the rubber bands, which is caused by the movement of air through the fuselage as indicated by the arrows in Fig. 4, will 50 cause the container 19 to be vibrated and thereby

permit the powder 25 to sift through the orifice in the bottom of the container and enter the tube 23. The rush of air through this tube will carry the powder rearwardly through the rear portion of the fuselage and outwardly through the rear opening 13, and thereby leave a stream of powder in the wake of the plane which may be given different formations to produce the desired sky-writing effect.

The orifice in the bottom of the container 19 may be small enough to prevent the powder from sifting through it when the plane is not in motion and the container is not being vibrated. This will also cause the powder to pass slowly from the container 19 and thereby assure an even flow of powder during the movement of the plane and conserve the supply thereof.

I claim:

1. A toy airplane comprising a fuselage having a passage extending therethrough to permit the passage of air currents longitudinally through said fuselage, wings extending from opposite sides of the fuselage, an elongated stretchable member stretched across the said passage and adapted to vibrate under the influence of air currents passing therethrough, a container for a powdered material supported upon said stretchable member and having an orifice therein to permit the passage of powder therefrom when the container is vibrated upon the vibration of said elongated stretchable member; the said powder being dispensed into the passage extending through the fuselage and expelled from the rear of said fuselage to thereby imitate sky-writing during movement of the airplane through the air.

2. A toy airplane comprising a fuselage having an opening therethrough to permit the passage

of air currents longitudinally through said fuselage, wings extending from opposite sides of the fuselage, an elongated stretchable member stretched across said opening and adapted to vibrate under the influence of air currents passing therethrough, a container for powdered material supported upon said stretchable member and having an orifice in the bottom thereof to permit the passage of said material from the container when it is vibrated by the vibration of the stretchable member, an air tube extending longitudinally of the fuselage in said opening and in the path of air currents passing therethrough; the said air tube having an opening in the upper wall thereof in communication with said orifice to receive the powder dispensed from said container and place it in the path of the air currents passing through said tube whereby the powder will be mixed with the air currents as they pass through said air tube and be expelled from the end of the fuselage to imitate skywriting.
